UNITED STATES PATENT OFFICE.

WILNER E. JOHNSON, OF BROOKLYN, NEW YORK.

DOOR-CONTROL DEVICE FOR VEHICLES.

1,093,629.

Specification of Letters Patent. Patented Apr. 21, 1914.

Application filed October 3, 1913. Serial No. 793,204.

To all whom it may concern:

Be it known that I, WILNER E. JOHNSON, a citizen of the United States, residing in the borough of Brooklyn, county of Kings, 5 and State of New York, have invented certain new and useful Improvements in Door-Control Devices for Vehicles, of which the following is a full and clear specification.

This invention relates to door-controlling 10 means for vehicles in which it is desired to utilize the platform space adjacent the doorway, for seats at times when such doorway is not in use for the entrance and exit of passengers.

15 The primary object of the present invention is to provide an improved device for controlling the opening and closing movements of the door in such a manner that when a movably mounted seat is in seating position adjacent the doorway, the door is not only locked, but the motive power which enables the door-operating motor to shift the doors, is automatically cut off. Thus the car door is rendered dead until such time 20 as the seat is removed from seating position, the locking means being automatically released by the seat movement which simultaneously permits a supply of motive power to the door operating motor.

25 Other and further objects will appear in the specification and be specifically pointed out in the appended claims, reference being had to the accompanying drawings which exemplify my invention in its adaptation 30 to a rapid transit vehicle provided with an air brake system.

In the drawings,—Figure 1 is a general 35 diagram of one embodiment of my invention; Fig. 2 is a fragmentary top plan view 40 of the door-locking device in locked position; Fig. 3 is a rear elevation of the same, parts being shown in section; Fig. 4 is a front elevation of a portion of Fig. 2 taken from the right of Fig. 2; Fig. 5 is a fragmentary side elevation of the operating connection between the seat and the motor operating circuit, parts being broken away and parts shown in section; Fig. 6 is a diagrammatic view of another embodiment of my invention; Fig. 7 is a fragmentary rear elevation of portions shown in Fig. 6; Fig. 8 is a side elevation of the same.

45 Referring first to the embodiment shown in Figs. 1 to 5 inclusive, the door 1 of the 50 vehicle is adapted to be moved into and out of closed position with reference to a door-

way, by means of a motor comprising in the present embodiment, a cylinder 2 within which is reciprocably mounted a piston 3. Said piston is provided with a piston rod 4 having an upwardly projecting portion 5 which is connected by a rod 6 to the door 1. A supply pipe 7 which may be connected up with any suitable source of any suitable fluid pressure medium, is according to the present embodiment connected to a valve housing 8, within which is mounted a valve (not shown) which may be turned by a handle 9 into either of two positions represented by full lines and dotted lines in Fig. 70. 1. Leading from the valve housing 8 is a pipe 10 which is connected to a valve housing 11, said valve housing 11 being connected by a pipe 12 with one end of the cylinder 2. The other end of the cylinder 2 is connected by a pipe 13 with another portion of the valve housing 11. Said other portion of the valve housing 11 is in turn connected by a pipe 14 with the valve housing 8, which is adapted to exhaust into the atmosphere by a discharge pipe 15. While the passage of the fluid pressure medium through the valve housing 11 may be controlled either in that portion of the valve 11 which is interposed between pipes 10 and 12 75 or within that portion of said housing which is interposed between the pipes 13 and 14, I preferably employ a valve which controls both portions of said valve housing simultaneously. For this purpose, a valve operating arm 16 (see Fig. 5) is secured to the valve rod 17, said arm 16 being provided with a slot 18, within which reciprocates a pin 19, which is carried by a projection or bracket 20 which is rigidly secured to the 80 seat 21. Said seat 21 is preferably mounted by trunnions 22 within suitable brackets 23, one of said brackets being mounted upon one wall 24 of the door housing. Reciprocably mounted within the wall or partition 24, is a locking bolt 25 which is provided on its inner end with an enlarged rounded end 26 to adapt it to be engaged by a cam surface 27 which is formed in a cam bracket 28 which is rigidly mounted upon the 85 seat 21.

90 By an inspection of Figs. 2, 3 and 4, it will be understood that when the seat 21 is down in seating position as shown in these figures, the cam surface 27 will force the 95 bolt 25 into locking position to positively bar the door 1 (see Fig. 2) from being shifted to

the left according to said figure. Furthermore, it will be understood that when the seat 21 is moved into unoccupied position, said bolt 25 will be permitted to retract under the action of a spring (not shown) so as to permit the door 1 to be opened. Referring now to the embodiment shown in Figs. 6, 7 and 8, the pipes 12 and 13 are connected to a common valve housing 29 which may be connected up with the air brake system of the vehicle, said air brake system not being represented on the drawings. Within the common housing 29 is a double valve (not shown), which is adapted to control the flow of fluid pressure medium through the pipes 12 and 13 in such a manner as to alternately drive the piston 3 to and fro for opening or closing the door 1 as the case may be. Surmounting the housing 29 is another housing 30 within which a solenoid (not shown) is suitably arranged to operate the double valve referred to above, said solenoid being grounded by a wire 31. Current from a line wire 32 may be supplied by a wire 33 leading to a contact 34, which is spaced from another contact 35, the space between said contacts being bridged when desired by an armature 36. Contact 35 is connected by a wire 37 with one of a pair of spaced contacts 38, the other of said contacts 38 being connected by a wire 39 with the solenoid within housing 30. According to this embodiment of my invention, the seat 21 is provided with a resilient contact 40 which is adapted to bridge the space between contacts 38 when the seat 21 is in raised position represented by the full lines in Figs. 7 and 8 but which prevents the energizing of the solenoid in housing 30 when the seat is in lowered position and in use.

The operation of my improved device will now be readily understood and briefly described as follows: When the handle 9 is moved into the position shown in full lines in Fig. 1, motive fluid such as compressed air, is admitted through supply pipe 7 into the pipe 10 and if the seat 21 be in raised position, said fluid will pass through the housing 11 into pipe 12 and thence into cylinder 2. Immediately the piston 3 is moved to the right end of the cylinder 2 and the door thrown into open position shown in full lines in Fig. 1. Any air or fluid which may remain in the cylinder 2 to the right of piston 3, is displaced through the pipe 13, lower portion of housing 11, pipe 14, and exhaust pipe 15. When it is desired to close the door, the handle 9 is thrown into dotted line position shown in Fig. 1, whereupon the motive fluid is admitted to pipe 14 from the supply pipe 7, passing in a reverse direction into the right end of cylinder 2 and forcing piston 3 to the left. During this operation the fluid in the left end of said cylinder is

displaced through pipe 12, housing 11, pipe 10 and exhaust pipe 15. If, however, the seat 21 is in lowered or seating position, the bolt 25 will be projected into locking position as shown in Figs. 2 and 4. Furthermore, the valve arm 16 will be thrown into dotted line position shown in Fig. 5, in which position the flow of fluid is prevented through both portions of the housing 11. In consequence, not only is the door barred against being opened but the motive power for effecting the opening movement is automatically cut off.

In the modification shown in Figs. 6, 7, and 8, whenever the seat 21 is in raised position indicated in dotted lines in Fig. 1 and in full lines in Figs. 7 and 8, the door-locking bolt 26 is in retracted position (see Fig. 7). In consequence the door 1 is free to be moved and if the plate 36 is made to bridge the space between contacts 34 and 35, the solenoid within housing 30 is energized by the circuit including feed wire 32, wire 33, contacts 34, 35, and 36, wire 37, contacts 38 and 40, wire 39, and ground wire 31. When this occurs, the fluid pressure medium is caused to flow into one end of the cylinder 2 and out of the other end thereof, the door 1 being thus opened or closed as the case may be.

What I claim is:

1. In a vehicle, the combination with a door, of operating means therefor, a seat movable into and out of seating position adjacent said door, and means operated by said seat for controlling the operation of said door-operating means.
2. In a vehicle, the combination with a door, of operating means therefor, a seat movable into and out of seating position adjacent said door, means operated by said seat for controlling the operation of said door-operating means, and locking means for said door adapted to be operated by said seat.
3. In a vehicle, the combination of a door, a motor for said door, means for controlling the operation of said door motor, and a movable seat adapted to actuate said motor controlling means.
4. In a vehicle, the combination of a door, a motor for said door, a seat movable into and out of seating position adjacent said door, and means operated by said seat for rendering said door motor operative and inoperative successively.
5. In a vehicle provided with a doorway, a door for said doorway, means for operating said door, a seat movable into and out of seating position adjacent said doorway, and an operative connection between said door-operating means and said seat, said door-operating means being adapted to be rendered operative and inoperative successively by said operating connection when the seat is shifted in position.
6. In a vehicle provided with a doorway,

the combination of a door for said doorway, a motor for moving said door, means for locking said door, and a movable seat adapted to control said door-operating motor and 5 said door-locking means.

7. In a vehicle provided with a doorway, the combination of a door for said doorway, a motor for moving said door into and out of position closing said doorway, a seat movable into and out of seating position adjacent 10 said doorway, and means for controlling the flow of motive fluid through said door-operating motor, said means being operably connected to said seat.

15 8. In a vehicle provided with a doorway, a door for said doorway, a motor for imparting the opening and closing movements to said door, an inlet valve for said motor, and a seat movable into and out of seating position adjacent said doorway, said seat being 20 suitably connected to said valve to control the operation of said door-motor to correspond to the position of said seat.

9. In a vehicle provided with a doorway, a 25 door for said doorway, a motor for imparting the opening and closing movements to said door, an outlet valve for said motor, and a seat movable into and out of seating position adjacent said doorway, said seat being 30 suitably connected to said valve to control the operation of said door-motor.

10. In a vehicle provided with a doorway, a door for said doorway, a motor for imparting the opening and closing movements 35 to said door, a combined inlet and outlet valve for said motor, and a seat movable into and out of seating position adjacent said doorway, said seat being suitably connected to said valve to control the operation 40 of said door-motor.

11. In a vehicle provided with a doorway, a door for said doorway, a motor for said door, a pipe for motive fluid leading to said

motor, a discharge pipe leading therefrom, a valve in one of said pipes, a seat movable 45 into and out of seating position adjacent said doorway, and means for connecting said valve to said seat.

12. In a vehicle provided with a doorway, a door for said doorway, a motor for said door, a pipe for motive fluid leading to said motor, a discharge pipe leading therefrom, a valve in each of said pipes, a seat movable 50 into and out of seating position adjacent said doorway, and valve operating means 55 connected to said seat.

13. In a vehicle provided with a doorway, a door for said doorway, a motor for operating said door, means for operating said motor, including a controlling member, a 60 seat movable into and out of seating position adjacent said doorway, and means for transmitting motion from said seat to said controlling member.

14. In a vehicle provided with a doorway, a door for said doorway, a fluid pressure motor for operating said door, means for controlling the inlet of fluid to said motor and outlet of fluid therefrom, a seat movable 65 into and out of seating position adjacent said doorway, and means for connecting said seat to said fluid - inlet and outlet controlling 70 means.

15. In a vehicle provided with a doorway, the combination of a door for said doorway, 75 a compressed air motor connected to said door for moving the same into and out of closed position, an air-control valve connected to said motor, a seat movable into and out of seating position adjacent said doorway, and a valve-operating arm connected to 80 said seat.
